FACING FOR FIRE PLACE CASING.

No. 14,383.

Patented Oct. 30, 1883.

UNITED STATES PATENT OFFICE.

ARTHUR OSBORNE, OF HYDE PARK, MASSACHUSETTS, ASSIGNOR TO
WILLIAM H. JACKSON, OF NEW YORK, N. Y.

DESIGN FOR A FACING FOR A FIRE-PLACE CASING.

SPECIFICATION forming part of Design No. 14,383, dated October 30, 1883.

Application filed August 3, 1883. Term of patent 7 years.

To all whom it may concern:

Be it known that I, ARTHUR OSBORNE, a citizen of Great Britain, residing at Hyde Park, county of Norfolk, State of Massachusetts, have invented and produced a new and original Design for the Facing or Frieze of a Fire-Place Casing, of which the following is a specification, reference being had to the accompanying drawing, forming part thereof.

10 The drawing represents a front elevation of my newly-designed facing or frieze.

The prominent features of this new design, viewed in elevation, consist of figures in relief representing a two-wheeled chariot or 15 car, with guard-railing upon its seat above an ornamented body, which is on an extended platform, a charioteer standing thereon, holding the reins to guide four rampant steeds harnessed abreast to the car, and a group of 20 maidens with garlands on a recessed bordered panel.

The background of the panel has a vari-formed undulating surface in bas-relief. The 25 four rampant steeds are at the left, the car and charioteer at the center, and the group of youthful female figures, offering garlands of laurel, standing facing toward the steeds and their driver, occupy the right hand end of the panel. The female figures are represented 30 with flowing robes and long waving hair, with girdles and sandaled feet, and two of them in

the foreground have their hands joined. The group of maidens of female figures have their right hands and arms extended, as in the act of casting boughs and garlands toward the 35 charioteer as he seems to be speeding onward, with drapery streaming rearward from his shoulders. The border inclosing the panel consists of the representation of a row of transverse dentilations between beaded moldings. The corners of the frieze are finished with rosettes of eight leaves and a central button, as shown. Two similar rosettes are interposed in the line of the border at the bottom of the design, near each end thereof. 40

I claim as my invention—

The design for a facing or frieze for a fire-place casing herein shown and described, consisting of figures in relief, of a car mounted by the charioteer at the center, four rampant 50 steeds harnessed to the car at the left, and a group of females, in loose robes, offering garlands to the charioteer at the right hand end of the panel inclosed with a dentilated border. 55

Witness my hand this 9th day of July, A. D. 1883.

ARTHUR OSBORNE.
